UNITED STATES PATENT OFFICE.

WILLIAM F. SCHULTZ, OF RIPON, WISCONSIN.

VACUUM TANK.

Application filed October 11, 1923. Serial No. 667,958.

To all whom it may concern:

Be it known that I, WILLIAM F. SCHULTZ, a citizen of the United States, and resident of Ripon, in the county of Fond du Lac and 5 State of Wisconsin, have invented new and useful Improvements in Vacuum Tanks, of which the following is a description, reference being had to the accompanying drawings, which are a part of this specification.

10 This invention relates to improvements in vacuum tanks and more particularly to vacuum tanks for use in connection with internal combustion engines to transfer gasoline from the gasoline tank to the carburetor.

15 It is one of the objects of the present invention to provide a device of the class described having a very simple and efficient valve means for controlling the various ports of the tank.

20 A further object of the invention is to provide a device of the class described which automatically draws in gasoline from the vehicle tank and discharges it to the engine carburetor.

25 A further object of the invention is to provide a vacuum tank which is of very simple construction, is strong and durable, and is well adapted for the purpose described.

30 With the above and other objects in view, the invention consists of the improved vacuum tank and its parts and combinations as set forth in the claim, and all equivalents thereof.

35 Referring now more particularly to the accompanying drawing in which the same reference characters indicate the same parts in all of the views:

40 Fig. 1 is a longitudinal sectional view of the improved vacuum tank;

Fig. 2 is an enlarged fragmentary sectional view of the upper portion of the tank to show details of construction;

45 Fig. 3 is an enlarged detail view of the port and valve for the lower half of the tank, the dividing partition being shown in section;

Fig. 4 is an enlarged sectional view taken on line 4—4 of Fig. 2; and

50 Fig. 5 is an enlarged sectional view of the

inlet ports and valves and the mechanism for operating the valves.

Referring to the drawing, it will be seen that the numeral 8 indicates a vacuum tank of cylindrical form. The interior of the 55 tank is divided into an upper compartment 9 and a lower compartment 10 by means of a partition 11 welded therein. The lower compartment 10 is provided with an outlet 12 for connection with the carburetor (not shown) of a motor vehicle engine. Also a second outlet 13 is provided, closed by a plug 14, to permit the draining of the tank when desired.

The top of the tank 8 is closed by a cover 65 15 secured in position by screws 16. A hollow depending portion 17 projects from the underside of the cover into compartment 9 and a head portion 18 is positioned immediately above said depending portion and in 70 communication therewith, being secured by means of a bolt 19. As shown in Fig. 4, said bolt has a longitudinally extending aperture 20 therein and a transverse aperture 21 in 75 communication with aperture 20. Said head portion is formed with an internally threaded part 22 into which is threaded a tube or connection 23 which extends to the gasoline tank of the vehicle (not shown). Said connection is adapted to feed gasoline into 80 member 18 where it will pass through a screen 24 wrapped about the upper portion of said bolt 19 and through apertures 21 and 20. From thence, the gasoline will flow 85 through an opening 25 formed in the depending portion 17 and into the upper compartment of the tank, all of which will be hereinafter more fully explained.

Adjacent said head 18, an upstanding internally threaded portion 26 is formed having threaded therein a connection 27 which extends to the intake manifold (not shown) of the vehicle engine. Said portion 26 opens into a chamber 28 formed in the cover member which has threaded into its outer end 90 portion, an air supply tube 29. Valve seats 30 and 31 adapted to receive valves 32 and 33 control the respective openings between said chamber 28 and the intake manifold connection and the air supply tube. The 100

operation of said valves will be more fully explained hereinafter.

When the valve 32 is in open position, there will be a direct open communication between the interior of the tank and the intake manifold of the vehicle engine. If the vehicle engine is in operation, the action of the pistons will create a suction and the air will be exhausted from the interior of the tank, forming a vacuum therein. Consequently, the vacuum will cause gasoline to be drawn from the gasoline tank of the vehicle, through the connection 23 and bolt 19 into the upper chamber 9 of the tank. A float 34, within the chamber 9 is adapted to be raised or lowered, as the level of the gasoline within the chamber changes. Said float is carried by a longitudinally extending rod 35, the upper end of which is pivotally connected to a link 36, of fork-like formation with three arms 37, 38 and 39. The outer ends of the two outer arms 37 and 39 are pivotally connected to a downwardly depending bracket 40 by means of pivot bolts 41, while the arm 38 carries a stop bar 38' to bear against the bracket 40 to limit the movement of the parts when the float is in its lowermost position. An inverted V-shaped member 42 is also pivotally connected to the bracket 40 by said pivot bolts. A coiled spring 43 connected to the center arm 38 of member 36 and a bar 44 formed as a part of said member 42 imparts a quick motion to said member 42, as will be more fully explained. Projecting upwardly from the top of member 42 are a pair of spaced arms 45 arranged to receive therebetween a shaft 46 which connects said valves 32 and 33 and operates them simultaneously. It is obvious that when the level of gasoline within the chamber 9 rises, the float will rise, thereby raising rod 35. The movement of rod 35 will pivot said link 36, causing the extremities of the arms thereof to describe an arc. When the extremities of said arms reach a point to either side of a line drawn through the points 44, 47 and 48, the tension exerted by the coiled spring 43 will move the V-shaped member 42 and consequently said valves which are between the arms 45. As shown in Figs. 1 and 5, the valves have been moved to the right thereby opening the intake manifold port and closing the air port. When the float rises to a point at which the spring is to the left of point 47, the valves will be moved to the left, closing the intake manifold port and opening the air port. When the intake manifold port is closed, obviously the suction from the cylinders will be shut off and the air rushing in from the air port will equalize the air pressure within the chamber 9 and no more gasoline will be drawn from the gasoline tank.

At this point, it should be observed that

the two compartments within the tank are separated by said partition 11. Positioned centrally through said partition is a tubular elbow member 49, the top of which is covered by a plate 50 having a central aperture 51 to permit the rod 35 to pass through, and also of sufficient size to permit the flow of gasoline therethrough. The lower end of the elbow member is normally closed by means of a door 52 connected as shown in Figs. 1 and 3. When gasoline is being fed into compartment 9, as has been explained, the suction heretofore mentioned will draw said door tightly against the end of the elbow member and prevent any gasoline from flowing therethrough into the lower compartment. However, when the intake manifold port is closed, the weight of the liquid and incoming air will open said door and allow the gasoline to flow from the upper compartment to the lower compartment. From thence, the gasoline is free to flow through the outlet 12 to the carburetor of the engine. A tube 53 admits air to the lower compartment.

The operation of the vacuum tank is as follows: When the tank is empty, the air port will be closed and the intake manifold port open, as explained. Gasoline will then be drawn into compartment 9 until a predetermined level has been reached. The valves will then be snapped to a reverse position and the door 52 will open, permitting gasoline to flow into compartment 10 and to the carburetor. The level of the gasoline will, of course, lower until another predetermined level has been reached, when the valves will move to the first mentioned position, and the operation will repeat itself.

From the foregoing description, it will be seen that the improved vacuum tank for motor vehicles is of very simple and novel construction, and is well adapted for the purpose described.

What I claim as my invention is:

In a liquid feeding apparatus including a supply tank, an auxiliary vacuum tank and a source of suction, a valve arrangement for said vacuum tank comprising a pair of opposed ports opening to a common passage which communicates with the vacuum tank, a pair of valves for said ports respectively, a common valve stem on which they are mounted and spaced apart by distance different from that between the two valve seats, a U-shaped member engaging opposite sides of the stem and guiding it for oscillation for alternate seating of said valves, one valve controlling a connection with a source of suction, and the other controlling an atmospheric vent, and means controlled by the liquid in said tank to effect a quick oscillation of said valves, said last mentioned means comprising a float formed with a rod, a forked member pivotally con-

nected to one end portion of said rod, a downwardly depending member secured adjacent said common passage, and having the outer arms of said forked member pivoted thereto, said depending member cooperating with a portion of said forked member to limit the pivotal movement thereof, a V-shaped member pivoted to said depending

member, said V-shaped member carrying said U-shaped valve stem engaging member, and a coiled spring connected to said V-shaped member and to said forked member. ¹⁰

In testimony whereof, I affix my signature.

WILLIAM F. SCHULTZ.
